UNITED STATES PATENT OFFICE.

PHILIPPO L. E. DEL FUNGO-GIERA, OF NEW YORK, N. Y.

MINE-RELEASING DEVICE.

1,228,755.

Specification of Letters Patent.

Patented June 5, 1917.

Application filed May 11, 1916. Serial No. 96,803½.

To all whom it may concern:

Be it known that I, PHILIPPO L. E. DEL FUNGO-GIERA, a citizen of Switzerland, and a resident of New York city, New York, have 5 invented a new and useful Improvement in Mine-Releasing Devices, which invention is fully set forth in the following specification.

The present invention relates to marine or floating mines, and the particular object 10 of the invention is to provide a device for releasing said mines from a distant point, as from the shore. In devices of this character, it is frequently desirable, as in times of peace, to maintain the mines at a sufficient 15 distance below the surface of the water to prevent vessels and other floating objects from contacting with the same, and to effect the flotation of said mines at a desired time, in order that they may move into the path of 20 ships and other floating objects. Preferably, the mine-release is operated electrically.

The invention will be better understood by reference to the accompanying drawings, wherein—

25 Figure 1 is a longitudinal sectional view of the improved device; and

Fig. 2 is a top plan view of the anchoring device shown in Fig. 1.

Referring to the drawings, wherein like 30 reference numerals indicate like parts, 1 is a mine of any suitable construction, to the lower portion of which is secured a mooring-ring 2 to which is affixed one extremity of a coiled cable 3. The other extremity of this 35 cable 3 is divided into two parts 31 and 32 which are connected respectively to eyelets 7 and 7' screwed or otherwise attached to an anchor member 18. To this cable 3 is secured a cable member 4 which is also attached to mooring-ring 2, the other end of said cable member 4 being fixedly secured to the perforated extremity of a mooring-ring pin 6. A swivel 30 is preferably provided in the length of said cable member 4. 40 This pin 6 projects into an orifice 6' in the anchor member 18, and passes through a stuffing-box 9 that prevents water from passing into said orifice around said pin. A cover 8 secured in place by bolts or other 45 suitable members 31, retains the stuffing-box in position and assists the latter in rendering the anchor member water-proof at the point where the ring passes thereinto. This orifice 6' is closed at its lower end by a 50 plate 25 provided with a packing 27, which 55

plate and packing are secured in place by bolts or other suitable retaining members 26.

On a shaft or rod 13 within said orifice 6', there is pivoted a hook 14, the upper extremity of which projects into an opening in the 60 lower end of pin 6 and engages anti-friction rollers or wheels 10 mounted therein, and the lower extremity of which is provided with teeth which mesh with the teeth of a rack 15. This rack is of substantially U- 65 shape, and one leg or member thereof projects through a housing 20 fixedly mounted in any desired manner on the bottom plate 25. Within said housing is contained an expansion spring 21, one end of which bears 70 against a member 21' carried by the rack, and the other end of which engages against one of the walls of said housing. Under normal conditions, that is to say, when the hook 14 engages pin 6, the rack 15 is maintained in 75 the position shown in Fig. 1. When, however, the rack is released, by means hereinafter described, the spring 21 moves the same toward the left, thus rotating the hook 14 around its shaft 13 and removing the 80 upper end of said hook from the pin 6, whereupon the mine rises by reason of its buoyancy. Any desired means may be provided for releasing said rack, but preferably the means employed are electrical, and, as 85 herein shown, an electro-magnet 22' is employed. Associated with this magnet is a pivoted armature 22, one end of which engages a flange 15' on the rack 15 and holds the same in the position shown in Fig. 1. A 90 spring 23 assists in holding the parts in the position illustrated in that figure.

The electro-magnet 22' may be actuated by any suitable source of power as, for example, the dynamo 19', which is connected to said 95 magnet by conductors 19; and, when the electric circuit is closed at 19', the electro-magnet will be energized, the armature will be moved about its pivot, thus releasing the rack 15, and the hook will be removed from 100 the pin 6. Thereupon the mine will, by reason of its buoyancy, rise to a predetermined position. At the point where the conductors 19 pass through the anchor member, packing 17 is provided to prevent the 105 ingress of water, and, within the orifice 6' of the anchor member 18, the conductors 19 pass through a magnetic indicating-box 24 which operates, in a well-known manner, to indicate at the operating station that the de- 110

vice has operated or functioned to release the mine.

Under normal conditions, that is to say, before the mine has been released so that it is free to rise under the influence of its buoyancy, it is maintained in the position shown in Fig. 1, in which the lower end of the mine 1 projects into a cage formed by the members 5 that are secured to the anchor member 18 by means of bolts or other suitable retaining means 11. These members 5 are preferably four in number, and to their upper extremities is secured a ring 5'. A slight leeway is provided therein to permit the mine 15 to swing with the movement of the water. Anchor-rings 12 may also be attached to the member 18, if desired.

While, for the purpose of clearness, one embodiment of the inventive idea has been 20 herein shown and described with considerable detail, it is manifest that the inventive idea is susceptible of various mechanical expressions within the limits of the appended claims.

25 What is claimed is:—

1. In combination, a floating mine, an anchor therefor, a pivotally-mounted hook connecting said mine to said anchor, and electrically-operated means for turning said 30 hook about its pivotal axis to effect its disengagement.

2. In combination, a mine, an anchor member, means connecting said mine to said anchor member including an eyelet projecting into said anchor member, a pivoted hook engaging in said eyelet, and electrically-operated means for moving said hook around its pivot to release said eyelet to permit said 35 mine to rise under the influence of its buoyancy.

40 3. In combination, a floating mine, an anchor member, means connecting said mine and anchor member including a pin provided with a perforation and extending into said anchor member, a pivoted hook engaging said perforated pin, and electrically-operated means for moving said hook about its pivot to release said pin and permit the mine 45 to rise under the influence of its buoyancy.

Copies of this patent may be obtained for five cents each, by addressing the "Commissioner of Patents, Washington, D. C."

4. In combination, a floating mine, an anchor member, means connecting said mine and anchor member including an apertured pin and a pivoted hook engaging therewith, a spring tending to disengage said pin and hook, and electrically-operated means for 55 maintaining said spring under compression.

5. In combination, a floating mine, an anchor member, means connecting said mine and anchor member including an apertured pin and a pivoted hook engaging therewith, 60 said hook being provided with teeth, a rack engaging the teeth on said hook, a spring urging said rack in a direction to move said hook about its pivot and disengage said hook and pin, and electrically-operated means for 65 maintaining said spring under compression.

6. In combination, a floating mine, an anchor member, means connecting said mine and anchor member including an apertured pin and a pivoted hook engaging therewith, 70 said hook being provided with teeth, a rack engaging the teeth on said hook, a spring urging said rack in a direction to move said hook about its pivot and disengage said hook and pin, a detent for maintaining said 75 spring under compression, and an electromagnet for operating said detent to release said spring.

7. In combination, a floating mine, an anchor therefor, a pivotally mounted hook connecting said mine to said anchor, a spring normally tending to disengage said hook, a detent opposing the action of said spring, and electrically-operated means for operating said 80 detent.

8. In combination, a floating mine, an anchor member, means connecting said mine and anchor member including an apertured pin and a pivoted hook engaging therewith, a spring tending to disengage said pin and hook, a detent for normally holding said hook in engagement with said pin, and electrically-operated means for operating said 85 detent.

In testimony whereof I have signed this 95 specification.

PHILIPPO L. E. DEL FUNGO-GIERA.
